UNITED STATES PATENT OFFICE.

KARL G. BAREIS, OF MADISON, WISCONSIN.

CHECK-HOOK.

SPECIFICATION forming part of Letters Patent No. 473,107, dated April 19, 1892.

Application filed June 19, 1891. Serial No. 396,795. (No model.)

To all whom it may concern:

Be it known that I, KARL GEORGE BAREIS, an ex-subject of the Emperor of Germany, having taken out first naturalization papers as a 5 citizen of the United States, residing at Madison, in the county of Dane and State of Wisconsin, have invented certain new and useful Improvements in Check-Hooks; and I do hereby declare that the following is a full, clear, 10 and exact description of the invention, which will enable others skilled in the art to which it appertains to make and use the same.

This invention relates to check-hooks; and it has special relation to certain improvements 15 upon the device covered by Letters Patent No. 446,277, granted to me February 10, 1891.

The object of the invention is to provide a check-hook of this class of such construction whereby the strength and durability are 20 greatly enhanced and which will furthermore possess advantages in point of simplicity, inexpensiveness, and general efficiency.

In the drawings, Figure 1 is a perspective view illustrating the application of my invention. Fig. 2 is a detail perspective of the same 25 detached. Fig. 3 is a vertical longitudinal sectional view.

Corresponding parts in all the figures are 30 denoted by the same letters of reference.

Referring to the drawings, A designates a solid post, which may be of any adapted or ornamental construction, and is preferably provided at its lower end with an enlarged base, said post being designed to receive the 35 checkrein. From the under side of the post projects a stem B, threaded at its end, and upon the latter is adapted to be screwed a nut c, whereby the device is secured to the harness-saddle.

From the rear side of the post A, nearer its 40 lower end, projects horizontally a lug C, bifurcated to form a vertical recess c'. D designates an arm, which is provided with a forwardly-projecting lug d, the latter being seated in the recess c and pivoted therein, whereby a hinge-joint is formed for the arm D. From near the upper end of the latter 45 projects forwardly a stud D', which is adapted when the arm is in normal position to en- 50 gage a recess a therefor in the post, and thus form an endless opening S, through which the

checkrein passes, and is held against accidental disengagement from the post. The upper end of the arm D is extended above the stud D' and forms a lug d', by which the 55 latter is withdrawn from engagement with the post.

For retaining the arm D in normal position a spring E is provided, which is secured at its lower end to the rear side of the base A'. 60 From its secured end the spring curves upwardly against the rear face of the arm and exerts its tension to retain the stud D' in engagement with the recess therefor.

The operation and advantages of my invention will be readily understood by those skilled in the art to which it appertains. To adjust the checkrein, the arm D is drawn rearwardly by means of the lug d', thus withdrawing the stud D' from the post A, when 70 the checkrein may be looped over the post. When the arm is released, the stud engages the recess in the post, and consequently locks the checkrein against accidental engagement. It will be further obvious that the present 75 invention is of such a construction as to permit the post A to be formed solid, whereby the strength and durability of the device are greatly increased.

I claim as my invention—

The herein-described check-hook, consisting of an upright solid post having an enlarged base provided with a securing-stem, said post being provided with a recess or indenture near its upper end and with an integral bifurcated lug at its lower end projecting at right angles to the post, an arm provided near its upper end with a stud normally engaging said recess or indenture and at its lower end with a lug projecting in the same 90 direction as said stud and pivoted in the bifurcated lug, and a flat spring rigidly secured to the under side of the base and curved upwardly in close contact with the outer side of the pivoted arm, substantially as and for the 95 purpose set forth.

In testimony whereof I affix my signature in presence of two witnesses.

KARL G. BAREIS.
